UNITED STATES PATENT OFFICE.

JOSEPH SLEPIAN, OF WILKINSBURG, PENNSYLVANIA, ASSIGNOR TO WESTINGHOUSE ELECTRIC & MANUFACTURING COMPANY, A CORPORATION OF PENNSYLVANIA.

ELECTRON-TUBE SYSTEM.

Application filed January 31, 1921. Serial No. 441,121.

My invention relates to means for preventing power loss in electron tubes and, more particularly, to means for causing the voltage impressed upon the tube and the current flowing therethrough to vary in a square-top manner.

One object of my invention is to increase the efficiency and rating of an electron tube by decreasing the amount of heat produced within the tube.

Another object of my invention is to provide simple and durable apparatus for producing the current and the voltage waves above mentioned.

Formerly, where the voltage impressed upon, and the current passing through, the electron tube was of sinewave shape or other form in which the current and the voltage were not of the square-top type, there was considerable loss in the tube because of heating effects. These heating effects reduced the effective rating of the tube and operated largely to reduce its efficiency.

In order to make my invention more clearly understood, I have shown, in the accompanying drawings, systems for carrying the same into practical effect, with the understanding that the arrangement of the several necessary elements may be varied without departing from the spirit of the invention.

In the drawings:

Figure 1 diagrammatically illustrates an embodiment of my invention in which power is taken from the plate circuit of the tube to supply the primary of an induction furnace.

Fig. 2 is a diagram showing the variations in voltage of the tube.

Fig. 3 is a diagram illustrating the variation in current corresponding to the voltage variation shown in Fig. 2.

Fig. 4 is a diagram illustrating the variations in potential of the grid of the tube.

Fig. 5 is a diagram illustrating the equivalent circuit for the power transformer in which the induction furnace operates as a secondary.

Fig. 6 is a diagrammatic view of a modified means for producing square-top voltage and current waves in an electron-tube system without employing a high-speed commutator.

In Fig. 1 is shown an electron tube 1 hav-

ing a filament element 2, a grid element 3 and a plate element 4. The filament element 2 is heated by means of a suitable "A" battery 5 which may be regulated to furnish the desired amount of current. The plate circuit is supplied from a direct current source 6 of high potential, through tapping the mains. In this case, the high-potential, direct-current generator 6 takes the place of the customary "B" battery but it is to be understood that any high-potential, direct-current source may be used.

In the grid circuit of the tube 1 is a "C" battery 7 the leads from the positive and negative terminals of which are connected to brushes 8 and 9, respectively. The brushes 8 and 9 are adapted to bear against a high-speed commutator member 11 diagrammatically illustrated. The high-speed commutator member 11 comprises two sections, a conducting section 12 and an insulating section 13. A brush 14 is adapted to continuously bear against the conducting section 12, and is connected to the grid 3 of the electron tube 1. The high-speed commutator 11 allows potential from either the positive or the negative side of the "C" battery 7 to be applied to the grid 3 and, in its rotation, both positive and negative potential will be applied to the grid.

In the plate circuit of the electron tube 1 is located an inductance 15 that operates to furnish the primary current for an induction furnace 16 that is diagrammatically illustrated in section. The induction coil 15 induces currents in the furnace 16 which heat the charge.

The internal heating in an oscillator tube, or in any other translating device, is a summation of the instantaneous I^2R losses. If, therefore, the internal resistance of an oscillator tube should be suddenly changed from a negligible small value to an extremely large value, the tube will either transmit current with a negligibly small voltage drop across its terminals and with a negligibly small I^2R loss, or it will not transmit any material quantity of electricity, the resistance drop across the terminals of the tube being then substantially equal to the total impressed electromotive force in the circuit, and the I^2R loss being again negligibly small. The internal heating in ordinary oscillator tubes thus occurs almost entirely dur-

ing the intervals when the resistance has a finite value, that is, when it is changing from an extremely low value to an extremely high value, or vice versa, and, with this thought as a starting point, I have devised a method and means whereby very considerable economies in operation, and increased ratings of already existing tubes, may be obtained.

- 10 For the theory of operation of my system, a study of the curves shown in Figs. 2, 3 and 4 will be of assistance. The voltage of the grid 3 is varied in a square-top manner, as indicated in Fig. 4. When the grid is 15 positive, the impedance of the tube is negligibly small and hence the voltage across the tube terminals is negligibly small, but when the grid is negative, the impedance of the tube is extremely high and 20 hence the voltage across the tube is substantially that of the direct-current source 6, all as indicated by the curve shown in Fig. 2. The current is displaced in respect to the voltage so that, when the voltage is at a 25 minimum, the current is at a maximum and vice versa, as explained hereinabove and illustrated in Fig. 3. This relationship will minimize heating in the tube. However, it is to be understood that the ideal waves 30 and conditions diagrammatically shown can only be approximated.

Since the direct-current source 6 furnishes a constant impressed electromotive force, and since the tube takes alternately substantially all of said electromotive force and substantially none of it, as indicated in Fig. 2, the voltage impressed upon the external load circuit has a square-topped formation substantially similar to the curve shown in 40 Fig. 3. Since the tube is a unidirectional conductor, the current in the work circuit cannot reverse and hence must fall to zero during the intervals in which the tube has an extremely high impedance. As is well-known, a square-topped unidirectional wave, such as that shown in Fig. 3, may be resolved, by the Fourier series, into a direct-current component, a fundamental sine wave, and a series of harmonics, usually of 45 diminishing magnitudes, the even harmonics being absent if the two half cycles are symmetrical.

For many purposes, the above wave shapes are not permissible, and net works that will 50 take voltages as above indicated with most of the direct-current component lacking and which will operate as actual load circuits are necessary to the proper functioning of my system. One net work which will take 55 such voltages and currents is a high reactance shunted by resistance. Evidently, if a square-top current is sent through this combination, the direct-current component will pass through the reactance, while the 60 alternating-current component will practi-

cally all pass through the resistance, giving a square-top voltage wave.

A transformer operating under load has an equivalent circuit similar to a reactance shunted by resistance. In Fig. 5 is shown 70 the equivalent circuit of a transformer having small leakage-flux reactances 17 and 18, as indicated. The load is indicated by the resistance 19. If the leakage-flux reactances are not too large the transformer 75 will operate in a manner similar to high reactance shunted by resistance. In Fig. 1, the primary induction coil 15 of the induction furnace 16, operates to supply the power to a secondary that is, in fact, the 80 charge to be heated or the crucible containing the charge, and hence, a circuit operating with such a load will be practicable with my flat-top-wave-generator tube.

In the operation of the system shown in Fig. 1, the filament 2 is caused to emit electrons, and the grid 3 has its potential changed by the rotation of the high-speed commutator member 11. The conducting portion 12 of the commutator member 11 comes alternately into contact with the brush 8 and the brush 9. The potential on the grid 3 of the tube 1 is, therefore, changed in a square-top manner. The high-potential direct current from the source 6 supplies the direct current for the plate circuit, and this direct current, in combination with the current resulting from the change in voltage of the grid 3, will give a voltage curve for the plate circuit corresponding to the curve shown in Fig. 2 and a current curve corresponding to the curve shown in Fig. 3. The inductance 15 operates as the primary of a transformer the secondary of which is the charge in the induction furnace 16 or the 1 crucible in which the charge is contained. This transformer is one with small leakage reactance, and, therefore, the equivalent circuit of the transformer will operate as a high inductance shunted by resistance. 1 Hence, the conditions necessary for efficient operation of the tube are present.

It is to be understood that many other alternating-current translating devices may be used in place of an induction furnace in 1 my system, and that the fundamental sine wave may be taken from the square-top wave. This induces heat generation in the external circuits, but heat production within the tube is greatly reduced over present practice, and thus, the rating of the tube may be radically increased.

In the modification illustrated in Fig. 6 is shown an electron tube 21, having a filament element 22, a grid element 23, and a plate element 24. The filament is heated by a suitable "A" battery 25, the amount of current flowing being controlled to produce the proper electron emission. A "C" battery 26 applies negative potential to the grid 23.

In the plate circuit of the tube is located a "B" battery 27 for furnishing direct current to the plate circuit.

Located within the plate circuit is a battery 28 in series with a rectifier 29, and, in parallel with the battery 28 and the rectifier 29, is a battery 30 and a rectifier 31. The rectifier 29 prohibits current passing through that branch of the circuit except 10 in one direction, and the battery 28 opposes, by its potential, the flow of current in that direction. Therefore, if current will flow through the circuit containing the battery 28 and the rectifier 29, the voltage in 15 the plate circuit must be built up to overcome the potential of the battery 28, at which time the current will break through, giving a square-top voltage. Likewise, in 20 the circuit containing the battery 30 and the rectifier 31, the potential of the battery 30 is opposed to the electromotive force in the plate circuit. The rectifier 31 allows current to flow in but one direction which is exactly opposite to that of the rectifier 25 29. Thus, in the other half of the cycle of the alternating current, the current may break through the rectifier 31 and the battery 30 but only when the electromotive force of the plate circuit has been built up 30 to a point to overcome the potential of the battery 30. The current then breaks through, giving a square-top voltage. Therefore, these batteries and rectifiers operate to insure that the current, flowing through 35 the portion of the circuit containing them, induces a square-top voltage.

In parallel with these two circuits containing a battery and rectifier each, is an inductance 32 located in inductance relation 40 to an inductance 33 in the grid circuit of the tube. When a difference of potential is impressed upon the divided circuit 29-31, in a direction opposed to the battery 28, it will cause current to flow in the coil 32 and will 45 build up a field in this coil. When this difference of potential reaches such a value that it exceeds the potential of the battery 28, the direction of electromotive force at the rectifier 29 is reversed and this rectifier 50 changes its character from a great impedance to a practically nil impedance. Consequently, the electromotive force impressed upon the coil 32, while current is flowing in the plate circuit, due to the conducting 55 condition of the tube, rises abruptly to a certain maximum fixed by the battery 28 and then is continued at that maximum.

When the current in the plate circuit terminates, the field in the coil 32 causes an 60 electromotive force to be impressed upon the divided circuit 29-31. This electromotive force is in a direction opposed to the battery 30. When it exceeds the electromotive force of the battery 30, the direction of electromotive force through the rectifier 31 is re-

versed, with the result that the impedance of this rectifier changes suddenly from a great to a small value. Consequently, the electro-motive force exerted by the coil 32 at the time when no current is flowing in the plate 70 circuit, rises abruptly to a certain value and cannot exceed that value.

The relations between the currents in coil 82 and coil 33 are expressed by the following equations:

$$L_1 \frac{di_1}{dt} + M \frac{di_2}{dt} = E_1$$

$$M \frac{di_1}{dt} + L_2 \frac{di_2}{dt} = E_2$$

80

in which L_1 and L_2 are the self inductances, M the mutual inductance, i_1 and i_2 the currents and E_1 and E_2 the electromotive forces in the respective coils. The current i_2 is a 85 constant and equal to zero because the grid circuit is an open circuit. Consequently, the second terms on the left-hand side of these equations are zero. Therefore, the equations show that the electromotive forces E_1 and E_2 bear a constant ratio but it has been shown by the above discussion that the electromotive force E_1 rises abruptly to a certain value, continues constant, changes abruptly to a certain value of the opposite 90 sign and again continues constant. Since the two electromotive forces have a constant ratio, the electromotive force E_2 changes in this same square-wave fashion. This is the reason why, in discussing the current 95 through the divided circuit 29-31, it was stated that this current stops and starts abruptly. It will be seen, by considering the cycle of actions, just described, that this assumption is not arbitrary, but is a consequence of the structure disclosed. It results from the abrupt change in the conductivity of the rectifiers 29 and 31, when the direction of the electromotive force through 100 them is reversed.

The output circuit of the tube 21 furnishes an illustration of the statement above, that many types of load beside that specifically described in connection with Figs. 1 and 5, may be used advantageously with a tube 105 giving a square form of wave. The illustration chosen shows the application to a load requiring an alternating current corresponding to the fundamental frequency of the square-form wave but from which the 110 direct current component and the more powerful of the harmonics must be excluded.

Within the plate circuit is located a frequency trap 34 comprising an inductance 115 35 and a capacitance 36 in parallel, shunted by a resistance 37. This frequency trap 34 is resonant to the third harmonic and acts to absorb the energy of the third harmonic in accordance with well known principles of voltage resonance. A frequency trap 38, 120

125

130

comprising an inductance 39 and a capacity 40, in parallel, shunted by a resistance 41, is resonant to the fifth harmonic and absorbs the energy of that harmonic. Within the 5 plate circuit is located an inductance 42 operating as the primary of a transformer from which the output of the tube may be utilized. The inductance 43, shown inductively coupled to an inductance 42 and operating as the secondary of the transformer, is located in a circuit carrying the load.

In operation, the tube 21 is adjusted to function as a continuous generator of oscillations, by reason of the "feed-back" transformer coupling 32, 33 between the plate circuit and the grid circuit. The filament 22 emits electrons, and the flow of current in the plate circuit has its third and fifth harmonic removed by the frequency traps 34 and 38. In that portion of the circuit connected in parallel with the inductance 32, which functions as a primary of a transformer the secondary 33 of which is in the grid circuit, are located the two circuits connected in parallel and having a battery 28 and a rectifier 29 and a battery 30 and a rectifier 31 respectively, as has been previously described. The rectifiers and batteries in each circuit are so arranged that 20 current may flow through one branch in one direction only, and the electromotive force of any current which flows is opposed to the electromotive force of the battery in that branch, so that, when current does finally 25 pass, the voltage will have been built up to such a high value that the current will break through in a square-top manner. This is true of the parallel connection except that current for the other half of the cycle only 30 passes.

The inductance 32, connected in parallel with the batteries and rectifiers, insures that the grid 23 will be excited in a square-top manner, through the mutuality of inductance between plate and grid circuits. This causes the current output to remain of square top form and to correct any tendency for the higher harmonics of current to shift relative to the fundamental. The effective 45 current flowing in the inductance 42, that operates as the primary of a transformer, the secondary of which is the inductance 43 located in the circuit carrying the fundamental frequency load, is substantially of 50 sine-wave conformation. This causes a certain amount of loss of energy in the external circuits but the added efficiency of the tube more than compensates for this loss. It 55 will be unnecessary to discuss the passage 60 of current through the transformer, comprising the primary 42 and the secondary 43, since this has been fully explained in connection with the operation of what is shown in Fig. 1, taken in connection with 65 what is shown in Fig. 5.

It is evident that there will be losses appearing as heat in resistances 37 and 41 and in the parallel resonant circuits. These losses may be large enough to make the theoretical efficiency of the whole system 70 less than that of a similar transformer 42-43 fed by an ordinary regenerative vacuum-tube oscillator. Such a diminution in theoretical efficiency will often be more than counterbalanced by the circumstance that, 75 with the square-wave-form system, the losses occur mainly outside the tube where provisions for dissipating the heat can be provided more conveniently and inexpensively than inside the tube. 80

Since I have not shown all possible modifications of my invention that may occur to those skilled in the art, I desire that my invention shall be limited only by the scope of the appended claims and the showing of 85 the prior art.

I claim:—

1. An electron tube comprising a cathode, a plate, a grid, means causing the current in the plate circuit to be of square-top form, a 90 primary of a transformer in the plate circuit, means operating as a secondary in inductive relation thereto and located in the grid circuit and a load operating as high reactance shunted by resistance. 95

2. An electron-tube system comprising an electron-emitting cathode, a plate element, a grid element, means in the plate circuit insuring that the plate current passing through that portion of the circuit shall be 100 of square-top form and means coupling that portion of the plate circuit to the grid. 105

3. An electron-tube system comprising an electron-emitting cathode, a plate element, a grid element, means in the plate circuit 110 for insuring that the plate current passing through that portion of the circuit shall be of square-top form, an inductance in parallel to that portion of that circuit and an inductance in the grid circuit in inductive 115 relation to the first mentioned inductance.

4. An electron-tube system comprising an electron-emitting cathode, a plate element, a grid element, rectifiers in the plate circuit, batteries in the plate circuit and means 120 coupling that portion of the plate circuit containing the batteries and the rectifiers to the grid so that the grid may be excited in a square-top manner. 125

5. An electron-tube system comprising a plate element, a grid element, rectifiers in the plate circuit, batteries in the plate circuit, an inductance in parallel with that portion of the circuit containing the batteries and rectifiers and an inductance in the grid 130 circuit in inductive relation to the first mentioned inductance so that the grid will be excited in a square-top manner.

6. An electron-tube system comprising an electron-emitting cathode, a plate element, 135

- a grid element, means in the plate circuit insuring that the plate current passing through that portion of the circuit shall be of square-top form, means coupling that portion of the plate circuit to the grid and circuits resonant to the harmonics of voltage and shunted by resistance in the plate circuit.
7. An electron-tube system comprising an electron-emitting cathode, a plate element, a grid element, means in the plate circuit insuring that the plate current passing through that portion of the circuit shall be of square-top form, an inductance in parallel with that portion of the circuit, an inductance in the grid circuit in inductive relation to the first mentioned inductance and circuits resonant to the harmonics of voltage and shunted by resistance in the plate circuit.
8. An electron-tube system comprising an electron-emitting cathode, a plate element, a grid element, rectifiers in the plate circuit, batteries in the plate circuit, said batteries and rectifiers being so arranged that current will flow through the portion of the circuit containing them in a square-top manner, means coupling that portion of the plate circuit containing the batteries and rectifiers to the grid and circuits resonant to the harmonics of voltage and shunted by resistance in the plate circuit.
9. An electron-tube system comprising an electron-emitting cathode, a plate element, a grid element, rectifiers in the plate circuit, batteries in the plate circuit, said batteries and rectifiers being so arranged that current will flow through that portion of the circuit containing them in a square-top manner, an inductance in parallel with that portion of the circuit containing the batteries and rectifiers, an inductance in the grid circuit in inductive relation to the first mentioned inductance and circuits resonant to the harmonics of voltage and shunted by resistance in the plate circuit.

In testimony whereof, I have hereunto subscribed my name this 18th day of January, 1921.

JOSEPH SLEPIAN.
